E. W. Young
Suspension Bridge.

N° 95,402.

Patented Sep 28, 1869.

United States Patent Office.

EDWARD WILLIAM YOUNG, OF NEW STREET, SPRING GARDENS,
GREAT BRITAIN.

Letters Patent No. 95,402, dated September 28, 1869; patented in England, February 19, 1868.

IMPROVED BRIDGE.

The Schedule referred to in these Letters Patent and making part of the same.

To all whom it may concern:

Be it known that I, EDWARD WILLIAM YOUNG, of New Street, Spring Gardens, in the county of Middlesex, Kingdom of Great Britain and Ireland, have invented a new and useful Improvement in the Construction of Bridges; and I do hereby declare the following to be a full, clear, and exact description of the same, reference being had to the accompanying drawing, and to the letters of reference marked thereon.

This invention consists in the construction of bridges of a compound character, of which the essential characteristic is the supporting of a suspended structure or suspension-bridge by two cantilevers.

In such bridges, a portion of the superstructure at and for a certain distance on each side of the centre of the span, acts as a suspension-bridge, the parts between this and the piers acting as cantilevers.

The central or suspension part of the structure does not contribute in any way to the support of the side or cantilever portions.

In order to enable others skilled in the art to make and use my invention, I will now proceed to describe its construction and operation, reference being had to the accompanying drawing, which forms a part of this specification, and in which—

Figure 1 is an elevation, and

Figure 2, a plan of a bridge of a single span of three hundred feet clear on my improved system.

Figures 3, 4, and 5, modifications of the invention.

The central part, *a a'*, is a suspension-bridge one hundred and twenty in length, *a b* and *a' b'* being the cantilever portions of the structure.

In this example, the suspension-chains *c c* are braced by means of diagonals, *d d*, capable of acting either as struts or ties.

The cantilever portions, *a b* and *a' b'*, are formed of vertical struts *e e*, inclined tie-bars *f f*, a top member, *g g*, in tension, composed of metal in the form of links or plates, and a bottom member, *h h*, in compression.

The cantilevers *a b* and *a' b'* are supported by towers *i i*, and are secured by back-ties *k k*, anchored in the ground.

The suspensions-chains are allowed to bend freely at the points *a a'*, where they join the cantilevers, and also at the point *l l*, at the centre of the span.

The platform of the bridge is made capable of bending freely at points *m m* and *l l*.

Allowance for end motion, due to contraction and expansion, should be made at points *m m*.

The wind-ties *n n* for the platform are shown in fig. 2, on the left-hand half of the figure, and the wind-ties *o o*, for the top member of the cantilever on the right hand.

Fig. 3 represents a bridge on my improved system, with one centre and two side-spans.

In this example, the top member of the cantilever portions is curved, and the struts inclined at an angle with the vertical. Towers are also dispensed with.

p p', the suspended portion of the structure, is made rigid by means of diagonal bracing, *p q*, and *p' q'* are the cantilever portions.

Fig. 4 is an example of a bridge wherein rigidity in the suspension-bridge portion is effected by means of a horizontal truss, *r r'*.

Fig. 5 shows a mode whereby this system may be applied to bridges of several spans.

The alternate spans *v t—u w* are formed on my improved system, the portions *s s'* being suspension-bridges, which, in this case, are shown as formed of straight suspension-bars, held in position by light struts.

The other spans, as *t u*, are smaller, and the superstructure is formed of a bowstring truss, *x x'*, the dead weight of which is either wholly or partially counterbalanced by the weight of the structure in the adjoining spans, the strain being communicated by means of the chain *y y*.

When the spans *v t—u w* are loaded, span *t u* being unloaded, the resistance of the truss *x x'* to upward transverse strain enables it to perform the duty of an anchorage to these spans.

Again, when span *t u* is loaded, spans *v t—u w* being unloaded, the resistance of the truss *x x'* to downward transverse strain, prevents the superstructure of the spans *v t—u w* from being lifted out of position.

The method herein described of constructing the span *t u* is not claimed by me.

The form and arrangement of parts in the cantilever and suspended portions of the structure may be varied.

What I claim as my invention, and desire to secure by Letters Patent, is—

A bridge having two cantilever portions, and an intermediate suspended portion, all constructed substantially as described.

In testimony whereof, I have signed my name to this specification, in the presence of two subscribing witnesses.

EDWARD WILLIAM YOUNG.
